UNITED STATES PATENT OFFICE.

JAMES P. S. LAWRENCE, OF THE UNITED STATES NAVY, ASSIGNOR OF ONE-HALF TO THOMAS BURD ZELL, OF CHESTER, PENNSYLVANIA.

ANCHOR.

SPECIFICATION forming part of Letters Patent No. 710,918, dated October 7, 1902.

Application filed November 4, 1901. Serial No. 81,053. (No model.)

To all whom it may concern:

Be it known that I, JAMES P. S. LAWRENCE, a lieutenant-commander in the United States Navy, at present stationed at Thurlow, in the 5 city of Chester, State of Pennsylvania, have invented certain Improvements in Anchors, of which the following is a specification.

My invention relates to the well-known style of anchors having the flukes arranged 10 to oscillate with respect to the shank, such oscillation being in extent about one-quarter of a revolution, more or less, and limited by any suitable coacting means carried by the shank and the hubs of the fluke.

15 A further feature of my invention consists in reducing the number of parts necessary to form a finished anchor, and for this purpose one or more of the members may be cast together, a further feature of my invention being to provide means for retaining the flukes in connection with the other members of the anchor.

20 In the accompanying drawings, Figure 1 is a plan view of an anchor, illustrating the preferred form of my invention, the hubs of the flukes being shown in section. Fig. 2 is a sectional view taken on the line *b b*, Fig. 1; and Fig. 3 is a plan view of a portion of the anchor, illustrating a detail of my invention.

25 In the form of anchor as constructed by me and shown in Figs. 1 and 2 of the accompanying drawings I provide a shank 1, having an enlarged head 2, from the center of which, on opposite sides of the same, the shafts 30 or spindles 6^b project, carrying the flukes 5^b. The flukes 5^b are carried by hubs 7, which are provided with the usual fins 8, and enlarged heads 9 and 10 are formed at the ends of these hubs, the portion between said hubs 35 being reduced in diameter between such heads, as shown, and strengthened by means of the ribs 11. The flukes are cast as separate and distinct members and have their heads recessed at 16. Each fluke has a 40 through-opening, whereby it may be slipped over the shaft or spindle 6^b, the inner portion of said opening having a space 25 with radial walls 26, which coact with ribs 27, carried by the shafts or spindles 6^b, and thereby serve 45 to limit the movement of the flukes upon the hub. For the purpose of securing the flukes

50 to the ends of the shafts or spindles I may shrink a collar 18 on the end of the same after the fluke has been slipped into place, such collar fitting the recess 16 in the head of the fluke and being of such thickness that a 55 flush finished surface may be provided for both collar and head. Each of the flukes 5^b is independently mounted upon the shaft or 60 spindle 6^b, and consequently the collars 18 should fit so as to permit this free and independent movement.

55 In my improved form of anchor the head of the shank is rounded, as shown, and while it is of greater diameter than the hubs of the 65 flukes it is of less diameter than the full width of the fins, and hence will not interfere with such fins when the anchor is in use. The connection between the shafts or spindles and the enlarged head of the shank is rounded, 70 as shown, and in casting a fillet is by preference inserted at this point, so that the connection will be greatly strengthened and prevent a fracture.

75 For the purpose of having an anchor of the character illustrated in Figs. 1 and 2, and yet at the same time one whose flukes will be coupled together, so that their movement is simultaneous, I may provide the heads 9 with the extension-pieces 30, having interlocking 80 portions or fingers 31, so that when set together they will be locked against independent movement. These portions are suitably extended, so as to come over the rounded end 2 of the shank, and by providing each piece with 85 a projection and a recess there is no necessity of having rights and lefts.

90 My improved anchor is of simple construction, of few parts, and the connections providing for the movement of one part upon another are of such character and proportioned with relation to the other members that an exceptionally strong anchor is procured.

Having thus described my invention, I claim and desire to secure by Letters Patent—

95 1. The combination in an anchor, of the shank, a pair of flukes, a shaft or spindle formed integral with the shank and supporting the flukes, said flukes having hubs extending from the shank to the ends of the shafts and being permitted to oscillate with

respect to the shank, means carried by said flukes and coacting with the shaft or spindle for limiting the movement of the flukes, and means for securing said flukes to the shafts or 5 spindles, said flukes having recessed portions for the reception of the securing means.

2. The combination in an anchor, of the shank, a pair of flukes, a shaft or spindle formed integral with the shank and carrying 10 said flukes and so combined with said shank as to dispose the flukes on opposite sides of the same, said flukes having heavy hubs extending from the shank to the end of the shaft and being independently mounted and 15 free to oscillate with respect to the shank, means for securing said flukes to the shafts or spindles comprising collars to be shrunk onto the ends of the shaft or spindle, said flukes being recessed to receive said collars, and co- 20 acting means carried by said flukes entirely independent of the shaft or spindle and serving to connect the same whereby their oscillation will be simultaneous.

3. The combination in an anchor, of a shank 25 having an enlarged head, and shafts or spindles cast integral therewith, lugs carried by each shaft or spindle, independently-mounted flukes adapted to said shaft or spindle and having hubs extending from the shank to the 30 end of the shaft or spindle, means for limit-

ing the oscillation of the flukes, such means comprising internal recesses in said flukes with radial walls to engage the lugs of the shaft or spindle, and collars shrunk onto each end of the shaft or spindle for securing the 35 flukes in place, the hubs of said flukes being recessed to receive said collars.

4. The combination in an anchor, of a shank having an enlarged head and having a shaft or spindle cast integral therewith, lugs carried by said shafts or spindles, separate flukes adapted to said shafts or spindles and having recesses provided with radial walls coacting with said lugs to limit the oscillation of the flukes, said flukes having hubs extending from the shank to the end of the shaft whereby a long bearing is secured, and means for securing the flukes and shafts or spindles in proper relation to each other, said means comprising a collar shrunk onto the ends of 50 the shafts or spindles, the hubs of said flukes being recessed for the reception of said collar.

In testimony whereof I have signed my name to this specification in the presence of two subscribing witnesses.

J. P. S. LAWRENCE.
